SHOE DISPLAY TREE

John C. Baas, Pittsford, N.Y., assignor to Rochester Shoe Tree Co., Inc., Rochester, N.Y., a corporation of New York

Filed Mar. 15, 1963, Ser. No. 265,541
8 Claims. (Cl. 12—115.6)

This invention relates to an article for use in the display and sale of shoes. More particularly, the invention relates to a shoe tree having an improved and convenient construction for use in the display of shoes that are offered for sale.

When shoes are arranged for display to potential buyers, the most attractive appearance possible must be presented. For this reason, it is customary to insert in a shoe, that is to form a part of a display, a special kind of shoe tree that is known in the trade as a display tree.

A display tree performs the usual function of a shoe tree, of filling the shoe out, to have a taut appearance, free from creases and wrinkles. In addition, display trees are usually attractively finished in smooth, conservative tones, to enhance the appearance of shoes without distracting attention from them.

For window displays for the retail trade, however, the sign indicating the price of a pair of shoes is often a greater distraction than is necessary, and it is usually set up far enough away from the shoes to shift the prospect's focus of attention. Once the prospect's attention is lost, it may not be recaptured. Another disadvantage of a separate price tag is that it is extremely difficult to position in such a way that it is informative yet not distracting, so that extra time and thought on the part of a window dresser is required to make up a display.

One object of the present invention is to provide a simple means for displaying a price sign with a pair of shoes, that will not divert the focus of attention of a prospective customer away from the shoes.

Another object of the invention is to provide a means for informing a prospective customer of the price of a pair of shoes, without requiring the customer to look away from the pair of shoes to obtain the information.

A further object of the invention is to provide neat, compact, attractive means for indicating the price of a pair of shoes in a convenient, quietly attractive way that is not distractible.

A further object of the invention is to provide a new, attractive, and simplified form of price marker for a pair of display shoes that will simplify the work of a window dresser.

Other objects of the invention will be apparent herein-after from the specification and from the recital of the appended claims. To these and other ends, the invention resides in certain improvements and combinations of parts, all as will hereinafter be more fully described, the novel features being pointed out in the claims at the end of this specification.

In the drawings:

FIG. 1 is a top plan view of a display shoe tree and price display marker that is constructed in accordance with one embodiment of this invention;

FIG. 2 is a side elevation thereof, and

FIG. 3 is a fragmentary view thereof, partly in section, and on an enlarged scale.

Referring now in detail to the drawing by numerals of reference, the numeral 10 denotes generally a display tree. This tree comprises a fore part 11 and a back part 12 that are secured together in the usual way by a bar 14. The front end of the bar 14 is secured in the fore part 11 of the tree, in the usual way, to permit pivotal movement of the bar 14 relative to the fore part

2

11 of the tree in a vertical plane. The back part 12 of the tree is mounted on the bar 14 for spring-opposed sliding movement toward the fore part 11 of the tree from the normal position shown in the drawing.

5 The fore part 11 of the tree is formed with a front portion 15 that is formed to project into the toe of a shoe. This front portion is integral with an enlarged central portion 16 that is shaped to engage against the inner surfaces of a shoe to fill out the vamp. This central portion 16 in turn is integral with an upwardly projecting part 17 that is formed to engage against the tongue of a shoe.

10 The back part 12 of the tree is formed with a shank portion 20 and with a smoothly rounded heel portion 21, that is generally shaped like a human heel and that is contoured to fill the heel part of a shoe. The heel portion 21 of the tree is formed, at its upper end, with a forwardly projecting lip 22 through which a cylindrical bore 24 extends. The upper face of the heel and of the 15 lip together form a smooth, flat surface 25 that is inclined upwardly from its front edge to its rear edge. Three small holes 26 are bored into the face 25, in spaced relation to each other.

20 A thin, transparent, plastic plate 27 is disposed over the face 25. This plate 27 is shaped to conform to the shape of the face 25. It is formed with three dogs 30 that engage in the holes 26 and that are formed to hold the plate 27 in place over the face 25.

25 The plate 27 is also formed with a recess or surface depression 31 that has a similar contour, in plan view, to that of the plate itself, as shown in FIG. 1; and that extends to the front edge of the plate, to provide access to the recess from the front edge of the plate. A cardboard tag 32, that conforms in shape to the shape of the 30 recess 31, is inserted in the recess. The parts are proportioned so that the tag 32 is snugly received in the recess 31, between the confronting lower surface of the plate 27 and the flat upper face 25 of the tree.

35 A tree that is made in accordance with this invention provides a convenient and attractive means for displaying the price of a pair of shoes, when inserted in one of the shoes. Preferably, the shoe style number and its price are written on the tag 32, and the tag is then inserted in the recess so that this information is readily 40 visible through the plate 27.

45 When the tag 32 must be removed from its recess for any reason, a finger can be inserted through the bore 24 to engage the tag and shift it so that part of the tag projects from the recess at the front end of the lug 22, to permit the tag to be grasped and pulled from the recess.

50 When the tree is to be used in a display where the price is not to be included, the tag is removed. Alternatively, instead of removing the tag, it can be replaced by a piece of attractively colored cardboard that will enhance the overall effect of the display. Or, as a further alternative, the plate 27 can be removed entirely, so that the tree will have a substantially conventional appearance except for the presence of the three small holes 26 in the 55 face 25.

60 A display tree that is equipped with a price display tag, in accordance with the present invention, permits the display of a price tag as an integral part of the display of a pair of shoes, and can convey to a prospective customer pricing and other information without distracting the eye of the customer away from the display of the shoes themselves. Instead, the customer's focus of attention is maintained on the shoes. Moreover, since the price tag and display tree are combined, the task of the window dresser is simplified, not only by the elimination of the separate display stand previously required for the price tag, but also because the window display can be built 65 70

around the shoes themselves, rather than around a three part display consisting of two shoes and a separate price display sign.

While it is preferred that the transparent plastic plate be mounted on a flat face at the heel of the shoe, it is also possible to form an attractive price display area on the upwardly projecting portion 17 of the tree, or alternatively, on a rearward extension of this part of the tree. Moreover, the plate 27 itself can be used to carry printed indicia, to identify the manufacturer or seller of the shoes, or the like, in some location thereon that will not obstruct the view of the price tag.

While the invention has been disclosed herein by reference to the details of a preferred embodiment thereof, it is to be understood that such disclosure is intended in an illustrative, rather than in a limiting sense, and it is contemplated that various modifications in the construction and arrangement of the parts will readily occur to those skilled in the art, within the spirit of the invention and within the scope of the appended claims.

I claim:

1. A shoe tree comprising a forward portion and a pivotally connected heel portion, said heel portion being formed with a flat, exterior display surface thereon, an imperforate transparent member for engagement over said surface portion, and means for holding said member over said surface portion, said member being formed with a recess extending inwardly from one edge thereof to confront said surface portion and formed to removably receive a display card therein.

2. A shoe tree comprising a forward portion and a pivotally connected heel portion, said heel portion being formed with a relatively thin lip portion and with a flat display surface that extends over at least a part of said lip portion, a transparent, rigid member for engagement over said surface, said member being formed with a recess that is disposed to confront said surface and that is formed to removably receive a display card therein between said member and said surface, said recess extending to one edge of said member to permit the insertion and withdrawal of a display card in and from said recess respectively at said edge, and means for holding said member over said surface.

3. A shoe tree in accordance with claim 2 wherein said lip portion is formed with an opening that extends through said lip portion and that opens through said flat surface to provide access to a display card in said recess to facilitate its removal.

4. A shoe tree comprising a forward portion and a heel portion, said heel portion being formed with a relatively thin lip having a flat exterior display surface that extends over at least a part of said lip, a thin, transparent, rigid member for engagement over said surface, said member being formed with a recess confronting said surface and formed to removably receive a display card therein, said body being formed with a plurality of spaced holes in said surface, and said member having a plurality of fingers that are disposed to project from one face of said member for insertion in said holes respectively to hold said member in place.

5. A shoe tree comprising a body having a forward portion and a heel portion, said heel portion being formed with a forwardly projecting lip at its upper end, said heel portion having a flat, exterior display surface thereon that extends over at least a part of said lip, a thin, transparent, rigid synthetic plastic member for engagement over said surface and that is generally shaped to conform closely to the contour of said surface, said member being formed with a recess confronting said surface and formed to receive a display card therein, the recess in said cover member extending to one edge thereof to permit the insertion and withdrawal of a display card in and from said recess respectively at said edge, said lip being formed with an opening therethrough that opens through said flat surface to provide access to a card in said recess to facilitate removal of a display card from said recess, said body being formed with a plurality of spaced holes in said surface, and said member having a plurality of fingers that are disposed to project from one face of said member for insertion in said holes respectively, to hold said member in place over said surface.

6. A shoe tree comprising a forward portion and a heel portion formed with an upwardly extending part having thereon a substantially flat display surface, a transparent member for engagement over said surface, said member being formed with a recess confronting said surface and formed to removably receive a display card therein, and means for holding said member over said surface.

7. A shoe tree comprising a forward portion and a pivotally connected heel portion, said heel portion being formed with an upwardly extending part having thereon a substantially flat display surface, an imperforate transparent member for engagement over said surface, said member having one side thereof formed with a surface depression confronting said surface and formed to removably receive a display card therein, and means for holding said member over said surface.

8. A shoe tree having the construction specified in claim 7, said heel portion being formed with a plurality of spaced holes in said surface and said member being formed with a plurality of fingers projecting from one face of said member for insertion in said holes to secure said member on said heel portion.
